DESIGN FOR A HOLDER FOR MACHINE TOOL CUTTERS

Harry C. Wilson, Huntington Park, Calif.
Application July 29, 1943, Serial No. 110,792

Term of patent 14 years

(Cl. D54—14)

To all whom it may concern:

Be it known that I, Harry C. Wilson, a citizen of the United States, residing in the city of Huntington Park, county of Los Angeles, and State of California, have invented a new, original, and ornamental Design for a Holder for Machine Tool Cutters, of which the following is a specification, reference being had to the accompanying drawing, forming a part thereof.

Fig. 1 is a perspective view of a holder for ma-

chine tool cutters taken from top, front, and one side thereof, showing my new design;

Fig. 2 is a top perspective view thereof;

Fig. 3 is a side elevational view thereof; and

Fig. 4 is a front elevational view thereof.

I claim:

The ornamental design for a holder for machine tool cutters, as shown.

HARRY C. WILSON.
